Inventor,
G. F. Meacham

UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. **7,958**, dated December 29, 1874; application filed December 16, 1874.
[Term of Patent 14 years.]

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph, making part of this specification.

In the photograph, A represents the base, and B the body or main portion, of the casing of a soda-water apparatus, both of rectangular form. The top C is inclined on both sides from *a* to *b* and from *b* to *c*, so as to resemble a roof with a "lean-to." To the front and rear sides of the casing are secured the plates E E, each having the general form of a cross, being cut away on each side at *d*, so as to ex-

pose to view a portion of the casing B, the design thus produced being unique and ornamental.

What I claim as my invention, and desire to secure by Letters Patent, is—

1. The design for the casing of a soda-water apparatus, substantially as herein shown and described.
2. The design of the front and back plates E E, cut away on each side at *d*, each plate having the general form of a cross, substantially as shown and described.

Witness my hand this 10th day of December, A. D. 1874.

GEO. F. MEACHAM.

In presence of—

P. E. TESCHMACHER,
G. A. MEACHAM.
